UNITED STATES PATENT OFFICE.

JAMES S. MARTIN, OF PITTSBURG, PENNSYLVANIA.

BARGE OR OTHER BOAT.

SPECIFICATION forming part of Letters Patent No. 782,153, dated February 7, 1905.

Application filed October 2, 1903. Serial No. 175,445.

To all whom it may concern:

Be it known that I, JAMES S. MARTIN, a citizen of the United States, residing at Pittsburg, in the county of Allegheny and State of Pennsylvania, have invented new and useful Improvements in Barges or other Boats, of which the following is a specification.

This invention relates to a pressed - steel barge or boat and contemplates an improvement on the barge or boat disclosed in my application for Letters Patent of the United States filed September 9, 1903, Serial No. 172,507.

The present improvement includes in its organization a series of pressed-steel plates, ribs, and strengthening devices and wherein the bottom ribs are either disposed in longitudinal relation alone or combined in some instances with intersecting transverse bottom ribs and side ribs disposed as in the construction disclosed by the foregoing application. The arrangement of the bottom ribs longitudinally of the barge or boat is preferable in some constructions and uses, and, as will be hereinafter specified, said bottom ribs may be of any contour adapted for the purpose. By the use of longitudinal ribs any tendency to compression or strain due to endwise pressure is resisted.

The desirable lightness of the structure and reduction of tendency to leakage and springing of the several joints is present in the improved construction, and the capability of arranging the barge or boat for heavy or lighter work may also be obtained.

In the drawings, Figure 1 is a top plan view of a barge embodying the improved features of the invention and shown broken through at its central portion. Fig. 2 is a transverse vertical section through the form of barge shown by Fig. 1. Fig. 3 is a view similar to Fig. 2, illustrating the use of a different form of rib. Fig. 4 is a transverse vertical section through the barge, showing the employment of a cross-girder which may be used at regular intervals in connection with the form of rib illustrated by Figs. 1 and 2. Fig. 5 is a view similar to Fig. 4, showing a cross-girder in use with the form of rib illustrated by Fig.

3 having a reinforce. Figs. 6, 7, and 8 are detail horizontal sections through a portion of the side of the barge, showing the use of different forms of ribs. Fig. 9 is a detail transverse section of a portion of the barge, showing the longitudinal ribs of one form intersecting transverse ribs of a similar or any other contour. Fig. 10 is a detail cross-section of an inverted-U-shaped rib having a securing-flange arranged for attachment to an intersecting rib. Fig. 11 is a detail longitudinal section of a portion of the bottom of the barge, showing the rib struck up to form a seat for a filler-strip which is disposed over the joint of the sheathing-plates to simplify the assemblage of the several parts and reduce the labor incident to the completion of a tight joint. Fig. 12 is a transverse vertical section through a portion of the side of the barge, showing a modification in the arrangement of the upper end of the sheathing.

Similar numerals of reference are employed to indicate corresponding parts in the several views.

The essential feature of the present improvement is the use of longitudinally-disposed ribs of any contour desired in the bottom of the barge or boat. In some instances, as will be hereinafter clearly set forth, the longitudinal ribs may be intersected at intervals by and secured to transverse bottom ribs of a reinforcing nature.

Referring to Figs. 1 and 2, the barge or boat is made up of a series of longitudinally-disposed bottom ribs 1 of Z shape and side ribs 2 of similar or any other preferred contour which are formed with lower elbows 3, having their terminals secured to the outermost longitudinal ribs 1. A sheathing 4 is applied over the outer portions of the bottom ribs 1 and side ribs 2, and consists of a series of steel plates having overlapped secured edges 5. The lower flanges of the ribs 1 are secured to the several plates, and the outer flanges of the ribs 2 are similarly fastened to the plates constituting the side portions of the sheathing. The ribs 1 are preferably arranged to have the upper flanges thereof from the longitudinal center of the barge projected

outwardly toward the opposite sides of the latter, and this can be readily accomplished when an even number of bottom ribs are used. If an odd number of ribs is necessary in completing the bottom structure of the barge, they will be arranged as near as possible in the same manner as an even number of ribs. The side ribs 2 will also be preferably disposed to have their inner flanges projected from the 5 transverse center of the barge outwardly toward opposite ends of the latter, though this construction is not particularly essential in relation to the side ribs; but when the ribs are so disposed it gives uniformity to the general arrangement. At the opposite sides of 10 the bottom the plates have a single arcuate contour, as at 6, and continue into the side portions of the sheathing, and the lower terminals of the side ribs 2 conform in curvature 15 to the opposite lower portions of the bottom sheathing and are secured to the adjacent ribs 1 by flanges 7, the lower ends of said ribs 2 extending under the upper flanges of the ribs 1. The side portions of the sheathing are 20 continued over the upper ends of the ribs 2 by bending to provide a flat margin or edge 8 of such extent as to permit the practical application of pumps and other attachments 25 commonly found in barge constructions. The 30 longitudinal ribs 1 at the ends of the barge will be struck up or curved by bending to give the barge the proper shape at its opposite site extremities.

Fig. 3 shows a modification in the form of 35 the ribs, the bottom longitudinal ribs 9 being of channel contour with their flanges projected inwardly toward the longitudinal center of the barge. The side ribs 10 are also of a like contour or they may be of the same 40 shape as the ribs 1 and 2, heretofore described. The remaining features of construction shown by Fig. 3 are similar to those shown by Figs. 1 and 2, and like reference-numerals are applied thereto.

45 Figs. 4 and 5 illustrate means for reinforcing the barge at regular intervals, and consists of a cross-girder 11, Fig. 4, struck up at the ends to form seats 12 for the reception of the lower terminals of side ribs 13 of similar 50 contour. The ribs 11 and 13 have base-flanges 14, which are secured against the sheathing 4, and the lower portions of the seats 12 are elevated to fit over the flanges of the lower terminals of the ribs 13. Intersecting and attached to the girder 11 and ribs 13 are longitudinal ribs 15, which are shown as having the same contour as the ribs illustrated by Figs. 1 and 2, though it will be understood 55 that any form of ribs having a suitable contour may be substituted for the rib of Z shape. At the points where the ribs 15 pass through the girder 11 and ribs 13 flanges 16 are formed, which are riveted to the girder and ribs 13. The girder 11 and ribs 13 are

shown as having materially greater dimensions than the ribs 15 for the purpose of giving additional strength to the structure. It will be understood in this connection, however, that the proportions may be varied at will, and in some constructions the ribs 15 65 and side ribs may be of the same size and the girder 11 may be a rib of the same dimensions as the ribs 15. In Fig. 5 the same principle is embodied as in Fig. 4, with the difference that side ribs 17 are used with materially-enlarged lower extremities 18, the said ribs having flanges 19 secured against the sheathing 4. The longitudinal ribs 20 in this instance are of channel shape, and the outermost ones of said ribs intersect and pass 70 through the lower enlarged extremities 18 of the ribs 17 and have securing-flanges 21 attached to said extremities. The lower terminals of the ribs 17 are secured or held in close contact against the longitudinal ribs 20 next 75 to the outermost ribs, and the extremities 18 of the ribs 17 are connected by a cross-bracing rib or girder 22, which terminally overlaps the said ribs and has a lower flange construction 23, which bears upon and is attached to the upper flanges of the ribs 20 between the lower terminals of the ribs 17. By 80 this means the necessity of cutting through the girder 22 is avoided and the cost of construction materially reduced. The ribs 20 in this instance have auxiliary reinforcing-ribs 24 fitted therein to resist crushing strain and 85 generally increase the durability and effectiveness of the said ribs 20. The ribs 20, like the ribs 15 and bottom ribs, (shown by Figs. 3 and 2,) are arranged in regular position in 90 relation to the longitudinal center of the bar or so that the open sides thereof will be located inwardly as near as practical to so dispose them. The remaining features of construction shown by Figs. 4 and 5, aside from the modifications noted, will be the same as 95 illustrated by Figs. 1, 2, and 3.

Figs. 6 and 7 show horizontal sections of the side ribs to illustrate the use of different 100 shapes and respectively embody a Z shape and a channel shape. The contour of the side ribs may also be varied to an L shape, as shown by Fig. 8.

Fig. 9 shows a longitudinally-disposed Z-shaped rib 25 intersecting a similar or other shaped transverse rib 26, the portions of the latter bearing against the rib 25 being in the form of securing-flanges 27. The rib 26 also has a part of its base-flange structure 28 struck 115 upwardly to fit snugly over the lower flange of the rib 25. The flanges 27 of the rib 26 are clearly shown by Fig. 10, and it will be observed that the rib 26 is of inverted-U shape 120 to demonstrate that a further variation in the 125 form of the several ribs used may be adopted.

Fig. 11 shows a construction for accommodating the application of the longitudinal ribs

over a butt-joint or a number of said joints throughout the sheathing 4, the lower portion or flange of the ribs being struck up, as at 29, to provide a seat or embracing means for a 5 filler-strip 30 or what is ordinarily known as a "butt-strap" used to cover the abutting ends of the plates. This particular construction avoids the use of a filler under the full length of the ribs and provides for the formation of 10 a practically tight joint.

If it is desired to cover or provide the upper portion of the barge with a deck, the upper extremity of the sheathing 4 adjacent to the side ribs is bent outwardly to form a fender 31 (see Fig. 12) to support the said deck or cover. This fender will be continued around the upper portion of the barge, and when the cover or deck is applied the strength of the barge construction will not be in the least de- 15 teriorated.

The means for securing the ribs, sheathing, and other parts set forth may be varied at will; but rivets will be preferably used and variations may also be adopted in the kind of rivets 20 and the mode of applying the same. The mode of bending the ribs and sheathing where necessary to give the barge or boat a proper shape will be of any of the approved pressure methods. The girders or cross-braces will also be 25 disposed in such manner as to avoid interference with the loading and unloading operations of the barge. The stock used in the construction of the barge will be formed in proper shape and quantities within certain scales pro- 30 portionate to the dimensions of the barge to 35

be constructed and after such initial preparation of the stock barges of different sizes can be expeditiously completed.

Having thus fully described the invention, what is claimed as new is—

1. A barge formed from pressed steel having a series of longitudinally-disposed bottom ribs, side ribs terminally attached to the outermost bottom ribs, the latter ribs having upper flanges extending over the lower ends of the 45 side ribs and a sheathing secured to said ribs.

2. A pressed-steel barge composed of a series of bottom and side ribs, the bottom ribs being arranged in planes at right angles to the side ribs and having upper and lower angular 50 flanges, cross-girders arranged at intervals and having enlarged terminals embracing portions of and secured to the side ribs, said girders intersecting the longitudinal bottom ribs and having the flanges of the latter secured 55 thereto, and sheathing-plates connected to the ribs.

3. A pressed-steel barge composed of a series of bottom and side ribs, having end flanges, the bottom ribs being disposed longitudinally, 60 and an outer sheathing connected to said ribs and having the upper terminal thereof bent at an angle in relation to the upper extremities of the ribs to provide a supporting means.

In testimony whereof I affix my signature in 65 presence of two witnesses.

JAMES S. MARTIN.
